UNITED STATES PATENT OFFICE

2,443,102

CRIB ROBE

Bertha Braun Friedman, Inwood,
Long Island, N. Y.

Application April 9, 1946, Serial No. 660,724

3 Claims. (Cl. 2—114)

The present invention relates to sleeping garments for babies.

An object of the invention is to provide a novel and improved baby sleeping garment, which maintains the child constantly covered, from which it cannot wriggle itself out of, and yet provides ample freedom of movement of the wearer.

Another object hereof is to provide a novel and improved sleeping garment of the character mentioned, which is easy to put on and take off the child, maintains its comfort, is free of objectionable wrinkling which would bother the child in its sleep, and which can be designed as decorative in fashion as may be desired.

A further object hereof is to provide a novel and improved baby's sleeping garment of the type set forth, which is simple in construction, flat when not in use, whereby it is easy to be ironed, reasonably cheap to manufacture and efficient in carrying out the purposes for which it is intended.

Other objects and advantages will become apparent as this disclosure proceeds.

In the accompanying drawings forming part of this application, similar characters of reference indicate corresponding parts in all the views.

Fig. 1 shows the garment in nearly completed condition, as it appears laid out flat.

Fig. 2 is a front view of the complete garment.

Fig. 3 is a front view of a modified embodiment of said garment, in accordance with the teachings of this invention.

In the drawings, the garment is shown to consist of a bodice member indicated generally by the numeral 15, which comprises a front 16 having a cutout 17, and a back 18 which terminates at the waistline. Extending laterally from each side of the waistend edge of said back, is an elongated belt member 19. Extending downwardly from the front member 16, and laterally below the waistline of the garment, is an apron member 20. A—A indicates the top fold line between the back and front members of the garment.

Centrally downward from cutout 17 and extending substantially along the apron member 20, is a slit controlled by a slideable fastening or closure means 21, or other suitable buttoning means if desired. Along the waistline on the front 16 of the garment, extending from near said closure means 21, to the sides, are the respective members 22 and 23, stitched onto said front 16, by means of seam lines 22' and 23', whereby each of said members form tubular

structures. The numeral 24 indicates slits in the front portion of the garment, and 25 indicates tapes, each secured at one of their respective ends in the region of the waistline of said garment. The numeral 26 indicates seam lines along the respective sides of the bodice portion 15. This garment is best adapted for use when the child sleeps in a crib or carriage.

To dress the child in the garment, the latter is laid flat on the sleeping surface, with cutout 17 above the pillow. The slide fastener or "zipper" 21 is opened, whereupon the child is placed with its head resting on region 27 of the back 18, and its feet extending under the apron 20. The child is now covered with said apron portion and the "zipper" closed; the hands of the child lying within the roomy bodice 15, are accessible when necessary through the slits 24. The free end of the belt 19 at the side entrance to tube 28, is passed through said tube to extend out therefrom near the zipper line. Likewise, the free end of the other belt 19, which is at the side entrance to tube 29, is passed thereto to extend out therefrom near the zipper line. Such free ends of the respective belts 19, are then tied into a bow 30 for instance, after being drawn, so that bodice 15, snugly encompasses the child's waistline, permitting the child to turn in the garment about the line of its length, but not to any appreciable extent along said line. The tapes 25, are respectively tied to rails or fixed fittings which are usual in crib and carriage structures, while the bottom and side edges of the apron member 20, are tucked in under the mattress.

If desired, the bodice of the garment may be fashioned as 15' in Fig. 3, to include the closed sleeves 31. These garments may be of any suitable fabric materials in accordance with season and decorated as design and style may dictate.

The bodice 15 of the combined jacket and crib cover of Fig. 2, may be deemed "bunting bag" style, while bodice 15' of Fig. 3, is of the dress style. Of course, the bodice of garments embodying this invention, may be of any style, outline or size desired.

It is to be noted that the back 18 is smooth, permitting the wearer comfort, and that the limitations of movement afforded and imposed upon the wearer by the waistline belt, insures both comfort and safety, and means to avoid accidental suffocation. Also, it is preferred that the stitching 26 along the back member 18, shall be only above the belt members 19; such stitching ending along the lower portion of the sides of the back member at about points 18'.

This invention is capable of numerous forms and various applications without departing from the essential features herein disclosed. It is therefore intended and desired that the specific descriptions herein be deemed illustrative and not restrictive and that the patent shall cover all patentable novelty herein set forth; reference being had to the following claims rather than to the particular embodiments herein to indicate the scope of this invention.

I claim:

1. In a sleeping garment of the character described, an unruffled back member having its lower edge at the waistline, a pair of belt members, extending one from each side of the back member at the waistline, a front member forming a bodice with the back member; said bodice having an opening to admit the head of a wearer, an apron member extending downwardly from the front member and outwardly with respect to the length of the garment and a pair of tubular members substantially along the waistline of the garment only on the front member, extending substantially from the respective sides of the garment and terminating intermediate such sides; said belt members being adapted to be respectively positioned through the respective tubular members whereby their free ends extend outwardly from the adjacent ends of said tubular members and lie on the exterior of the garment.

ment and said free ends are adapted to be secured together when the garment is worn, whereby the front member is ruffled along the waistline and the back member remains unruffled.

5. 2. In a garment as defined in claim 1, wherein the front and back members are stitched only above the points of attachment of the belt members.

6. 3. A garment as defined in claim 1, including 10 a longitudinal opening in and intermediate the sides of the front member, closure means on said front member for said opening, and wherein the inward ends of the tubular members are in the region of said opening.

15 15 BERTHA BRAUN FRIEDMAN.
